United States Patent Office

Des. 209,355
Patented Nov. 21, 1967

209,355

AIRCRAFT

Lawrence Bernard Rellis, 734 NW. 80th, Apt. 16,
Miami, Fla. 33150

Filed Jan. 3, 1967, Ser. No. 5,271

Term of patent 14 years

(Cl. D71—1)

FIG. 4

FIG. 5

FIG. 6

FIG. 7

FIG. 1 is a perspective view of the aircraft showing my new design.

FIG. 2 is a side elevational view thereof.

FIG. 3 is a top plan view thereof.

FIG. 4 is a view of the opposite side thereof.

FIG. 5 is a bottom plan view thereof.

FIG. 6 is a front elevational view, and

FIG. 7 is a rear elevational view.

I claim:

The ornamental design for an aircraft, as shown.
